UNITED STATES PATENT OFFICE.

ARTHUR B. CLUNIES, OF ROCHESTER, NEW YORK, ASSIGNOR TO THE SILL
STOVE WORKS, OF SAME PLACE.

DESIGN FOR A FIRE-BRICK.

SPECIFICATION forming part of Design No. 24,244, dated April 23, 1895.

Application filed March 15, 1895. Serial No. 541,953. Term of patent 14 years.

To all whom it may concern:

Be it known that I, ARTHUR B. CLUNIES, a citizen of the United States, residing at Rochester, in the county of Monroe and State of New York, have invented and produced a new and original Design for Fire-Bricks, of which the following is a specification, reference being had to the accompanying drawings, showing the same.

In the drawings, Figure 1 is a perspective view of one end of the fire-brick; Fig. 2, a similar view of the opposite end; Fig. 3, a cross-sectional view, and Fig. 4 a longitudinal-sectional view.

The leading feature of my design consists in the configuration or shape of the brick.

The upper edge of the brick is rounded as shown at 1, and on the front near one end is the angular rib 2, merging into said rounded edge, the side of said rib nearest the end be-

ing more abrupt than the other, and the lower edge of the brick is cut away or chamfered at 3.

In the end of the brick nearest the rib 2 is a channel 4 and above this a shoulder 5 is formed.

The end of the brick shown in Fig. 2 is cut away at 6 and in said cut-away part is the channel 7 which extends toward the front and merges into the chamfer 3 in the lower edge of the brick. The upper end of the cut away portion 6 is rounded toward the back at 8, as shown in Fig. 2.

What I claim is—

The design for fire-bricks substantially as herein shown and described.

ARTHUR B. CLUNIES.
